UNITED STATES PATENT OFFICE.

ALFONSO CORTELLA, OF PHILADELPHIA, PENNSYLVANIA.

SOUND RECORDING AND REPRODUCING MACHINE.

1,341,011.

Specification of Letters Patent. Patented May 25, 1920.

Application filed December 18, 1916. Serial No. 137,540.

To all whom it may concern:

Be it known that I, ALFONSO CORTELLA, a subject of the King of Italy, and a resident of Philadelphia, county of Philadelphia, 5 and State of Pennsylvania, have invented an Improvement in Sound Recording and Reproducing Machines, of which the following description, in connection with the accompanying drawings, is a specification, 10 like characters on the drawings representing like parts.

This invention relates to talking machines. The invention aims to provide an improved machine of that nature for recording and reproducing a plurality of sound records successively and in repeated cycles. By this means an opera or any long musical or other record may be rendered with no break in the reproduction occasioned by the substitution of one record for another.

In the drawing of one embodiment of my invention illustrated and described herein—

Figure 1 is a front elevation;

25 Fig. 2, a partial plan of the record shifting mechanism on an enlarged scale;

Fig. 3, a partial vertical cross-section on an enlarged scale, on the line 3—3, Fig. 1;

Fig. 4, a detail front elevation of a part 30 of the record shifting mechanism on an enlarged scale, and

Fig. 5, a detail of the clutch or record locking means.

Referring first to Fig. 1, the illustrative 35 embodiment of my invention is shown as a multiple disk record machine and as comprising a suitable table or stand 1, having legs 2, 2, which may conveniently be made adjustable as to height by making them of 40 the telescoping type.

Mounted on the table 1, are a plurality, herein two, of turntable supports or brackets 3, 3, of suitable design which may be secured to the table 1, as by screws 4, 4. Each 45 support 3 is provided with suitable bearings, herein ball bearings 5, to receive a rotatable shaft 6 which carries at its upper end a turntable 7, which conveniently may be called a continuously rotatable record 50 carrying member, as normally it is always in rotation.

The upper end of the shaft 6, Fig. 5, is, in each case, provided with a series of crown teeth 8. The shaft 6 is hollow and receives 55 within it a spindle 9, carrying near its upper end a flange 10 also provided with a

downwardly extended tooth 11 which engages the teeth 8 on the shaft 6. The upper end of the spindle 9 is threaded to take a nut 12 by means of which a record disk 13 60 is secured to the spindle. These spindles may be called conveniently, successively operable record carrying members, as normally each member 9 is operated alternately, and the two successively upon being 65 thrown into operating relation with their turntable shafts 6.

For operating the turntables or continuously operable record carrying members, I 70 have provided the improved means which I will now describe.

On the table 1, see Figs. 1, 2, 3, and in the rear of the supports 3, is mounted, as by supports 14, a driving shaft 15, adapted to be operated in any convenient manner, 75 herein by a belt 16, from a motor 17, in this case secured to the under side of the table 1. Should it be desired to operate the talking machine in connection with a moving picture machine, obviously the shaft 15 could be 80 properly connected therewith for that purpose; and to that end the shaft 15 carries, at its left-hand end Fig. 1, a gear 18, in mesh with a second gear 18^a on a jack shaft 18^b adapted to be connected to the shaft of a 85 moving picture machine, not shown.

The shaft 15, Figs. 1 and 3, carries the necessary number, herein two, of spiral gears 19, 19, in mesh and coöperating with, in each case, a similar gear 19^b on each shaft 90 6. Both turntables being operated from the same driving shaft they are therefore operated always at the same speed with a uniformity that adds much to the quality of the sound reproductions, as the tones of the several disks containing one long record are produced at the same pitch. The record shifting mechanism is operated and controlled jointly through suitable connections, by the sound arms, to be described, and the 100 driving shaft, and I will now describe this record shifting mechanism.

On the table 1, see Figs. 1, 3, best shown in Fig. 3, and in the rear of the supports 3, is mounted, as by a support 20, a relatively 105 long spindle supporting and record shifting lever 21, provided at each end with a laterally extended arm or spindle support 22, which, at its outer end receives on its upper face the lower end of a spindle 9. These 110 spindles, by means to be described, are each alternately raised into inoperative position,

held there while its disk is not in operation, and then dropped into operative relation with its rotating turntable while the record on its disk is being reproduced.

5 The lever 21 is provided at its rear face with two lever positioning members 23, shown herein as horizontal arms. These lever positioning members 23, are, in turn, immediately controlled and acted upon in 10 each case by a smaller lever throwing member 24 pivoted also to supports 25 on the table 1. One end, herein the outer end, of each lever throwing member 24, Figs. 2 and 4, is positioned beneath a lever positioning member 23, while its opposite or inner end is positioned to be acted upon by a catch or dog 26, to be described. Each catch is controlled through suitable connections, by a tripping member, also to be described, one 20 on each sound arm 27, 28, in their travel across the record disks.

My novel means for controlling the movements of the record shifting lever 21 and spindle supports 22 by the sound arms is as follows. On the table 1, and in the rear of the lever 21, see Figs. 3, 4, is a forked standard 29 in each arm end of which is mounted to rotate a vertical spindle 30. Each spindle 30 carries thereon a catch carrying arm 31 locked thereto by a lock screw 32. Pivotal secured at the outer end of each arm 31, as by a screw 33, for horizontal movement thereon, is a knuckle 34, operatively a part of and having pivoted 35 thereto in turn, as by a screw 35, the upwardly movable catch 26 already referred to, the outer beveled end of which in each case rests upon the inner end of a lever throwing member 24 already referred to.

40 Each spindle 30 is actuated by means of an arm 36 rearwardly extended thereon as by a lock-screw 37, which arm in this case, is extended upwardly at its outer or rear end to contact with and to be actuated by 45 a tripping member 38 on a sound arm supporting bracket 39 which moves with the sound arm as it travels across the record tablet. It is obvious that the spindle 30, arms 36 and 31 together, although shown 50 as separate members secured together, constitute essentially a lever as effectually as though they were constructed of one piece, and they for convenience will be hereafter referred to as the reversing lever 30. The 55 bracket 39 has a pivot bearing 40 in a post 41 also on the table 1, and in the rear of the support 29. The upper end of the bracket 39 is secured to the sound arm 27 which has also an additional pivot bearing 42 at its elbow 43.

The sound arm has a sound opening 44 at its inner end which may lead to a horn or other sound discharging means, not shown, if desired, but in the present case, Fig. 1, 65 the sound arm is shown equipped with a

conventional form of sound magnifying device 45 having wires 46 leading therefrom, by means of which the sound can be carried to any desired point and greatly magnified as to volume.

For locking the shifting lever 21 in either of its positions, I have provided the locking levers 47, 48, at the respective ends thereof, pivoted to supports 49, 50, and adapted to overlie the ends of the lever 21 when in 75 locking position.

The edges 51, 52 of the outer ends of these levers adjacent the inturned ends of the lever 21 are beveled, Figs. 2 and 4, permitting the ends of the lever 21 to slide down 80 upon and past the beveled edges of the levers 51, 52, while the opposite or inner arms 53, 54, are connected by connecting rods 56, 57, to arms 58, 59, also secured to the levers 30, Fig. 3, as by locking screws 85 60, 61, and actuated and controlled by the tripping members 38. Stops 62, 63, are provided to limit the throw of the levers 47, 48, as a precaution and springs 64, 65 secured to the rods 56, 57, the stop 63 and 90 bracket 49 act normally to return the levers 47, 48, to normal locking position when permitted so to do by the arms 58, 59.

For positively acting upon the catch members 26 at the proper times to cause them to 95 depress the lever throwing members 24, and through the record shifting means effect the shifting of one record disk from operative to inoperative position and vice versa, there is provided suitable means which I will 100 describe.

On the driving shaft 15 already referred to, Figs. 1, 3, are two lever shifting disks 67, 68, which rotate continuously therewith. Each disk has extended laterally from one 105 face thereof directly over the adjacent end of the member 24 a pin 69. When either turntable with its record disk or tablet is in operative position, Fig. 1 right-hand end, the pin 69 on the corresponding lever shifting disk just clears the adjacent end of the member 24 in its rotation. When, however, the record has been reproduced and its turntable is to be raised into inoperative position its catch 26 has been thrown by the tripping member 38 and lever 30 into operative position and wedged between the member 24 and pin 69, as in Fig. 3, right-hand end, so that the pin 69, on its next rotation, will strike the member 26 on top, pushing it and 110 the end of member 24 thereunder downward. This causes the opposite end of member 24 to lift the adjacent lever positioning member 23 and thereby raise the corresponding end of the record shifting lever 21, carrying with 115 it its spindle 9 and the record disk secured thereto, thus disengaging the spindle 9 from operative relation to the shaft 6, stopping the rotation of the disk. Simultaneously with the foregoing operation, the opposite 120

turntable with its disk is thrown into operative relation with its shaft 6 and the reproduction of the record is begun.

While the operation of the turntable by 5 a motor as proposed, is ordinarily sufficiently uniform as to speed, nevertheless occasionally fluctuations in the voltage will cause a slight unevenness in the running of the motor which can be more or less overcome 10 by the use of a suitable regulator.

For this purpose I have provided a speed 70 regulating means which comprises a gear 70 on each shaft 6, and a worm 71 in mesh therewith, said worms carried by a shaft 72 15 mounted, for rotation in brackets 73, on the supports 3, and posts 74 on the table 1.

The shaft 72 is provided with a suitable 20 governor as the usual ball governor 75, and disk 76 fast thereon.

Between the posts 74 is a post 77, the lower 25 end of which is normally received in a longitudinal slot 78 in the block 79 on the table 1. The upper end of the post 77 is forked and each forked end is provided with a suitable 30 friction member 80, as leather, adapted to engage the face of the disk 76. This post 77 may be adjusted at will to regulate the friction between the member 80 and the disk 76 by means of a rod 81 rotatably supported by 35 the posts 82, 74, the rod having threaded connection with one of the posts and a suitable adjusting wheel 83 at its end.

The operation of my improved talking machine is as follows: With the several parts 35 in the positions shown in the figures of the drawings, the reproduction of the record on the Fig. 1 right-hand disk is completed, and the reproduction of the record on the left-hand disk is about to commence. As the 40 sound box for the right-hand record, Figs. 1, 3, traveled toward the center of the disk carrying its tripping member 38 to the position shown in Fig. 2, the adjustable screw 38^a on the tripping member 38 contacted 45 with the arm 36 on the spindle 30 and gradually moved the catch carrying arm 31 to the right, Fig. 3, throwing the arm 59 also to the right, and by means of the rod 57 and lever 48 unlocking the adjacent end of the lever 50 21. The movement of the arm 31 to the right caused the catch 26 to slide to the right on the adjacent end of the reversing lever 24 until the member 26 reached a point in the path of the pin 69 on the rotating disk 68. 55 The several parts are so adjusted that the member 26 reaches this point just as the needle of the right-hand sound box is shunted from the record groove still farther to the left by its record groove not shown. 60 The catch member 26 having arrived beneath the pin 69 on disk 68, the member is struck by the pin 69 on its first rotation thereafter, is thereby pressed down upon the adjacent end of member 24 and the latter is 65 depressed causing its opposite end to raise

the corresponding end of the record shifting lever 21 by means of the member 23 thereon thus carrying the right hand spindle 9 and its record disk resting on the support 22 upward into inoperative position.

The rod 57 has been moved against the spring 65 and when the sound box is raised by the operator and the sound arm 28 with its tripping member 38 carried back to starting position again for the next record, the 70 spring 65 returns the members 48, 57, 59, to their original positions. Simultaneously with the upward movement of the right-hand end of the lever 21, the opposite end moves downward, the lever end striking the 75 inclined face of the locking lever end 51 and, sliding thereon and beneath it as it yields sufficiently through the medium of the spring 64, is locked in position. The spring 80 85 64 throws the end 51 back and over the end of lever 21 and the reproduction of the record on the left-hand disk is begun.

As the sound box for the left-hand disk travels over the same toward its center the screw 38^a on the tripping member 38 contacts at the proper time with the arm 36 and, 90 causes the arm 31 to swing on the spindle 30 and carry the member 26 to the right toward and beneath the pin 69 on the disk 67, as described in connection with the opposite 95 member 26. This movement of the spindle 31 at the same time causes the arm 58 to travel in advance of the member 31 and, through the rod 56, to swing the outer end of the locking lever 47 to the left. This unlocks the adjacent end of the record shifting lever 21 preparatory to the raising of the same by the action of the pin 69 on disk 67, and member 26 in connection with the member 24 as already described when the record 105 is finished and the tripping member 38 engages the end of the arm 36.

When the left-hand lever end 21 is raised and the corresponding record thrown into inoperative position, the opposite end is 110 again depressed and its turntable, with a new record thereon, again thrown into operative relation and the reproduction of the record continued with no break therein. In this manner the continuous recording or reproducing of a record may be indefinitely continuing through the shifting of the record carriers in successive cycles.

The machine is simple in construction, positive and quick in its action for shifting 120 the record carriers. Doubtless modifications of the above described mechanism may be made within the spirit of the invention and scope of the claims.

Claims—

1. A sound recording and reproducing machine comprising a continuously operating record carrying member, an operating shaft therefor, a pintle for holding a record, means for locking the pintle in operative 130

- engagement with a carrying member, and a sound arm; and record shifting means including a record shifting lever having a pintle support, and a lever positioning member thereon, a lever throwing member for and integrally separate from the positioning member, and a lever tripping member actuated from the sound arm to depress the lever throwing member.
10. 2. A sound recording and reproducing machine comprising an operating shaft, continuously operating record carrying members, each having a pintle with means for locking it to its carrying member, and a sound arm; and record shifting means comprising a record shifting lever, positioning members thereon, and a lever throwing member adapted to raise each positioning member, and shifting lever locking means.
15. 3. A sound recording and reproducing machine comprising a continuously operating record carrying member, an operating shaft therefor, a pintle for holding the record, means for locking the pintle in operative engagement with the carrying member, a sound arm; and record shifting means including a record shifting lever having a pintle support and a lever positioning member thereon, a lever throwing member for
20. the positioning member, a vertically and laterally moving catch actuated by said sound arm to actuate the lever throwing member and record shifting member, and a shifting lever locking means actuated by the
25. sound arm.
4. A sound recording and reproducing machine comprising a continuously operating record carrying member, an operating shaft therefor, a pintle for holding the record, means for locking the pintle in operative engagement with the carrying member, a sound arm; and record shifting means including a record shifting lever, a pintle support, and a lever positioning member on said
30. lever, a lever throwing member for the positioning member, a vertically and laterally moving catch actuated by said sound arm to actuate the lever throwing member and record shifting member, a locking member for
35. the shifting lever also actuated by the sound arm in advance of the catch, and means for normally holding and retaining the locking lever in shifting lever locking position.
5. A sound recording and reproducing machine comprising a sound arm, a continuously operating record carrying member, an operating shaft therefor, a pintle for holding the record, means for locking said pintle in operative engagement with the carrying member; means for holding the pintle and record in inoperative position, comprising record shifting means, said means including a record shifting lever, a pintle support and a lever positioning member on the shifting lever; a lever throwing member for said po-

sitioning member, a vertically and laterally moving catch, a support, means on the support to engage said sound arm to actuate the lever throwing member and record shifting lever; a locking member for the shifting lever also actuated by the sound arm in advance of the catch, and means for normally returning the locking lever to and retaining it in shifting lever locking position.

6. A sound recording and reproducing machine comprising a sound arm, a sound magnifying and transmitting device connected therewith, a continuously operating record carrying member, an operating shaft therefor, a pintle for holding the record, means for locking said pintle in operative engagement with the carrying member; means for holding the pintle and record in inoperative position, comprising record shifting means, said means including a record shifting lever; a pintle support and a locking lever, a positioning member on the shifting lever, a throwing member for said positioning member, a vertically and laterally moving catch, a support, means on the support to engage said sound arm to actuate a lever throwing member and record shifting member; and a lever locking member also actuated by the sound arm in advance of the catch, and means for normally returning the locking lever to shifting lever locking position; and speed regulating mechanism including a governor operatively connected with the operating shaft and a tension device coöperating with the gov- 100

ernor.

7. A sound recording and reproducing machine comprising sound arms, simultaneously operated record carrying members, an operating shaft therefor, pintles for holding the records, means for locking the pintles in operative engagement with the carrying members; means for holding the pintles and records in inoperative position, comprising record shifting means, said shifting means including a record shifting lever, pintle supporting and lever positioning members on the shifting member, lever throwing members for the positioning members; vertically and laterally moving catches, a support, means on the support to engage the sound arms to actuate the lever throwing member and record shifting member; locking levers for the shifting lever also actuated on the sound arms in advance of the catches and means for normally returning the locking levers to shifting lever locking position.

8. A sound recording and reproducing machine comprising sound arms, simultaneously operating record carrying members, successively operating record carrying members, an operating shaft having lever shifting disks thereon; and means for successively throwing the successively operative 130

carrying members into operative relation to the simultaneously operative carrying members, including catch carrying arms with catches thereon operated from the sound 5 arms, a record shifting lever, and means for actuating the latter from the operating shaft including lever throwing members and catches actuated from the sound arms including the changing of the positions of the 10 catches relative to the lever shifting disks.

9. A sound recording and reproducing machine comprising sound arms, simultaneously operating record carrying members, successively operating record carrying members 15, an operating shaft having lever shifting disks thereon; and means for successively throwing the successively operative carrying members into operative relation to the simultaneously operative carrying members, including catch carrying arms with catches thereon operated from the sound arms, a record shifting lever, and means for actuating the latter from the operating shaft including vertically acting lever throwing 20 members and catches actuated from the sound arms, including the changing of the positions of the catches by laterally swinging catch carrying arms, relative to the shifting disks; and locking levers engaging 25 the shifting lever and operated also from the sound arms.

10. A sound recording and reproducing machine comprising sound arms, simultaneously operating carrying members, successively operating record carrying members superimposed thereon, an operating shaft having lever shifting means thereon; and means for successively throwing the successively operative carrying members into operative relation to the simultaneously operative carrying members including laterally swinging reversing levers operated from the sound arms with resiliently mounted vertically and laterally adjustable catches 45 thereon; a record shifting lever, and means for actuating the latter from the operating shaft including lever throwing members in juxtaposition to the operating shaft shifting means and adjusted to be actuated upon 50 the positioning of the catches between said lever throwing members and the operating shaft shifting means; and locking levers engaging the ends of the shifting lever and operated also from the sound arms.

55. 11. A sound recording and reproducing machine comprising record carrying members operating continuously, an operating shaft therefor, balanced successively operative record carrying members adapted to be

operated successively and simultaneously 60 with the first named carrying members; a sound arm, record and successively operated carrying-member-shifting means, including a shifting lever, a tripping member; and connections between the shifting means and tripping member including a reversing lever acting at substantially right angles to the shifting lever, a throwing lever, and a lever shifting disk on said shaft; and means for effecting operative engagement between the disk 70 and the throwing member and shifting lever.

12. A sound recording and reproducing machine comprising continuously moving record carrying members 7, means for operating the same, alternately operating record carriers 9 adapted also to be operated from the continuously moving members 7, the operating shaft 15, the record shifting lever 21 connected with and for alternately throwing one alternately operable record 80 carrier and its record into operation, and its opposite record carrier and record out of operation; and operating means therefor comprising tripping members 39 actuated from the tone arms, catch carrying arms 31 85 with catches 26 and knuckles 34 thereon and throwing levers 24; disks 67 on the shaft 15 acting upon the throwing levers 24; and connecting rods 56, 57, and locking levers 53, 54, secured thereto and actuated also 90 from the tone arms, for locking and unlocking the shifting lever 21.

13. A sound recording and reproducing machine comprising constantly operating record carrying members, alternately operating record carrying members supported during operation by and actuated by the constantly operating members, an operating shaft, means for locking the alternately operating record carrying members to the 100 constantly operating record carrying members, means for supporting the alternately record carrying members in inoperative position, including a record shifting lever, locking levers therefor, and means for actuating the record shifting lever; said means including throwing levers, catch carrying arms and catches thereon, means for operating the same from the tone arms; and means also operative from the tone arms for unlocking the record shifting lever in advance of movement of said lever, and means to lock the record shifting lever after movement of the same.

In testimony whereof I have signed my 115 name to this specification.

ALFONSO CORTELLA.
